[57] CLAIM

The ornamental design for a ceramic tile with screw heads, as shown and described.

DESCRIPTION

FIG. 1 is a perspective view of a ceramic tile with screw heads embodying my design;

FIG. 2 is a top view thereof;

FIG. 3 is a front view thereof, the back view, right side view and left side view being identical to the front view though reflecting the screw head slot orientation as shown in FIGS. 1 and 2;

FIG. 4 is a top view of a ceramic tile with screw heads embodying an second alternative embodiment of my design; and,

FIG. 5 is a front view of FIG. 4, the back view, right side view and left side view being identical to the front view though reflecting the screw head slot orientation as shown in FIGS. 4.
